UNITED STATES PATENT OFFICE.

PAULDING FARNHAM, OF GREAT NECK, NEW YORK, ASSIGNOR TO THE
TIFFANY & COMPANY, OF NEW YORK, N. Y.

DESIGN FOR A SPOON, FORK, OR SIMILAR ARTICLE.

SPECIFICATION forming part of Design No. 29,403, dated September 27, 1898.

Application filed March 5, 1898. Serial No. 672,785. Term of patent 7 years.

To all whom it may concern:

Be it known that I, PAULDING FARNHAM, a citizen of the United States, and a resident of Great Neck, in the county of Queens and State of New York, have invented a new and original Design for Spoons, Forks, or other Similar Articles, of which the following is a specification.

This invention relates to a design to be imparted to or wrought upon spoons, forks, and similar articles; and it consists of the novel ornamentation set forth in the accompanying description and drawings.

In the drawings forming part of this specification, Figure 1 is a front view of the handle of a spoon or fork, to which an integral portion of the design is applied. Fig. 2 is a rear view of such handle, to which another integral portion of the design is applied.

The unitary design comprises the front face A (shown in Fig. 1) and the rear face B. (Shown in Fig. 2.)

The parts A and B of the design are clearly

shown in the accompanying drawings, to which reference is made; and I do hereby declare that said drawings disclose to any one a clear understanding of the design and is sufficient to enable such person to use my invention.

What I claim as new, and desire to secure by Letters Patent, is—

1. In a design for a spoon, fork or similar article, the front face A, substantially as shown.

2. In a design for a spoon, fork or similar article, the rear face B, substantially as shown.

3. The design for a spoon, fork or similar article, consisting of the faces A and B, substantially as shown.

In testimony whereof I have signed my name to this specification in the presence of two subscribing witnesses.

PAULDING FARNHAM.
